Patented Oct. 23, 1973

228,803

STEREO CONSOLE CABINET

Lindburg Hunt, 2905 Charing Cross Road,
Falls Church, Va. 22042

Filed Apr. 4, 1972, Ser. No. 241,106

Term of patent 14 years

Int. Cl. D14—03

U.S. Cl. D56—4 C

FIG. 1

FIG. 2

FIG. 3

FIG. 4

FIG. 5

FIG. 1 is a perspective view of my stereo console cabinet as seen from the front and top thereof;

FIG. 2 is a perspective view of the stereo console cabinet of FIG. 1 as seen from the front and side thereof;

FIG. 3 is an end elevational view of the stereo console cabinet;

FIG. 4 is a front elevational view of the stereo console cabinet; and

FIG. 5 is an end elevational view of a modification of my stereo console cabinet wherein the front is curved. I claim:

The ornamental design for a stereo console cabinet, as shown.
